UNITED STATES PATENT OFFICE.

FREDERIC H. STROM, OF ST. PAUL, MINNESOTA.

SYNCHRONIZING ATTACHMENT FOR PHONOGRAFS.

Application filed April 18, 1927. Serial No. 184,784.

REISSUED

My invention relates to a device for providing continuous, uninterrupted musical accompaniment to motion picture films, by means of phonograph records, as required by 5 a cue sheet, chart, guide or other means for determining particularly appropriate musical themes to be played at certain "cues", titles, scenes or actions in said motion picture.

10 A further object is to provide musical accompaniment on one record selection or section of music for an approximate given or predetermined length of "action time".

"Action time" is here used and understood to be the length of time necessary to show or project a series of scenes or actions, independent of a fixed mathematical relationship as between projecting a given number of feet or film and a given number of 20 seconds; or as independent and distinct from a fixed period of time in which the relationship between the number of feet of film shown per second is and must be dependent upon the length and period of time necessary to reproduce the musical measures or sound waves in the record; or as distinct and independent from the perfect synchronization of film and recorded music; its fixed time relationship made obviously necessary 30 in order to maintain proper musical pitch. The object of my device is to maintain a certain amount of flexibility or independence of the speed of the projection machine; of broken film, or "cut outs" due to censorship; then at the moment of the showing or projection of the above mentioned "cue", scene or action, "fade out" the preceding section of music and "fade in" the succeeding selection without any audible break between the said sections or selections of 40 music; this being done by a manually operated electric synchronizing and volume control device as hereinafter fully set forth and illustrated in the accompanying drawings, in which:

Fig. 1 is a plan view of an electrically operated phonograph with two tone arms having electric pick-ups and showing one in playing position on a record, and the other 50 in non-playing position, adjacent the other record.

Fig. 2 is an enlarged sectional elevation about as at line 2-2 in Fig. 1, and showing particularly the switch throwing arm 11 of the tone arm in operative position.

Fig. 3 is a detail sectional view of a pre-

ferred type of switch operated by the said switch throwing arm, about as on line 3-3 in Fig. 2.

Fig. 4 is a schematic wiring diagram of the motor control means.

Fig. 5 is an electrical wiring diagram of a single synchronizing volume control as used in the use of my device.

Fig. 6 is a wiring diagram involving independent volume control and synchronizing means, this figure being a modification of Fig. 5.

Referring to the drawings by reference numerals, I will first describe the mechanical and electrical means of my device which operate the motors, and later the electrical means of synchronizing control, the latter in a preferred form particularly in Fig. 5, and a modified form in Fig. 6.

For a thorough understanding of my device, it is first required that an electric phonograph is provided having two turntables L and R, and a motor for each said table, as LM and RM for a left and a right turntable. 15R is a disc type record on the table R and 15L is a record on table L.

10 is an electric pick-up including the reproducing needle 10N, each said pick-up being on the free end of one of the horizontally oscillatable tone arms 16R or 16L of any suitable form and each said arm 16 pivoted at 17 rearwardly of the turntables, the two wires from each pick-up 10 being carried inside its tone arm to the volume 85 and synchronizing control which will be inafter be more full described.

My device provides the proper music for an entire photoplay, parts or themes being previously recorded in a predetermined rotation on a plurality of disc records with serial numbers or letters and such records as are not in use on the machine to be within reach of the operator and exchanged as needed and indicated by the chart. Such chart is not illustrated, it being sufficient to state that the progressive musical numbers are recorded on the records, the chart merely indicating the serial number of the record which should be played from one part of the photoplay to another predetermined part of the play. For example, an operator may be directed by the chart to play record as 15L, from its starting point for approximately two minutes. The chart may call for a change of music at a point in the photoplay which requires certain music to be played. The

electric pick-up 10R, is placed at the outer edge on record 15R, the V-switch 14R throws the circuit on for motor RM, which in turn drives the turntable R. As this record is 5 in full operation there is no music from this pick-up unit until the synchronizing control 18 is turned from position 18L as indicated by arrow 19 to 18R. As this control is moved around slow, the music on record 10 15L fades away, the music on record 15R comes in gradually and there is no break in the music. The blending in and out of the two strains of music is one of the objects of 15 my invention.

15 The V-switch 14 has an arm 12R which is moved by the switch throwing arm 11 to position 11A, which closes the circuit between 14R and 13R, which current is fed in from wall plug 20 through wire 21, 20 through wire 22, through motor RM, through wire 23, back to plug 20 immediately starting motor RM.

In the position that the tone arm 16L is 25 playing (as in Fig. 1), the switch 14L has a closed circuit from plug 20 through wire 21 and 24 through switch 14L, through arm 14A to contact 13L, wire 25, to motor LM, thence through wire 26 and 23 back to the wall plug 20.

30 The switch 14 has also a cushion 14C, which tends to muffle any metallic sound as the V-switch is thrown by the switch operating arm 11.

The audio transformer 27, (see Fig. 5), 35 has a primary circuit 27A leading to the proper power amplifier input (not shown), which sets up a secondary circuit 27B passing through terminal 28, wire 29 to terminal 30, with a lead-over 31 to terminal 32, 40 through wire 33 to electric pick-up 10R, through wire 34, to the terminal 35, through wire 36, to the terminal 18R and the resistance 18C, through synchronizing control 18A, through the wire 37, through terminal 45 38, through wire 39 back to the secondary circuit 27B of transformer 27.

When the synchronizing control 18A is moved as from 18A' to position 18F or thereabout, the resistance between 18R and 50 18F is increased and the resistance between 18F and 18L decreases. The current which goes through wire 33 decreases as current is increasing in wire 41 through the electric pick-up 10L, through wire 42, to the terminal 43, wire 44, to terminal 18L, and the resistance 18C to the synchronizing control 18F. When the synchronizing control 18F is moved into position 18G, the resistance between 18G and 18L is decreased to the 55 minimum. The electric pick-up 10L receives the full volume of the circuit, while the electric pick-up 10R is faded out.

In the modified form as shown in Fig. 6, the transformer 27 having a secondary circuit 27B, the current passes through to ter-

5 minal 28 to wire 29 to terminal 30 to lead over 31 to terminal 32, through wire 33, to terminal 44, through wire 45 to the electric pick-up 10R, through wire 46 to terminal 18R and the resistance 18C, through the 70 synchronizing control arm 18A and 18' through the wire 47 to the terminal 35, through wire 48 to the terminal 49, through the resistance 50 to the volume control 51', through the wire 52 to the terminal 38 to the 75 wire 39 to the secondary coil 27B. When the synchronizing control arm 18A is moved to the left or close to the terminal 18L the resistance increases between arm 18A and terminal 18R. The current will divert at 80 terminal 44 through wire 45' to the electric pick-up 10L, through the wire 53 to terminal 18L, thence to the synchronizing control arm 18A.

In this modified circuit, in case one or the 85 other of the electric pick-ups 10R and 10L is to be tuned out without tuning the other in or lowering the volume, the volume control 51' is moved toward the terminal 54, the circuit passes from terminal 32 through wire 90 55 to terminal 54, thence to 51'. The circuit then continues as described in the previous paragraph.

The scratch filter 56 is so arranged in 95 Figs. 5 and 6 between terminals 18L and 18R, that it cushions the resistance as it increases and decreases between said terminals and the synchronizing control arm 18A, which allows the current to be increased in 100 one pick-up unit and decreased in the other 100 pick-up unit uniformly without any interruption or vibration which brings a uniformly fading volume of music and simultaneous increasing volume of music.

I claim:

1. In an electric record playing machine having two record turn-tables, two oscillatable tone arms, an electric pick-up on each tone arm and suitable electric sound transmitting means to a tone chamber; an electric motor for each turn-table circuit closing and opening means operated by the oscillating movement of the tone arms for starting and stopping the corresponding motors; an electric circuit operatively connecting both 110 pick-ups, means in said circuit for controlling current selectively through said pick-ups and simultaneously increasing current through one while increasing current through the other to electrically produce sound from 115 either record as desired.

2. The structure specified in claim 1, and volume control means incorporated in said pick-up circuits, comprising a resistance coil and a rotary control engaging said resistance 125 and arranged to vary the current to the sound producing means.

3. The structure specified in claim 1, in which said motor starting and stopping means comprises for each tone arm, a finger 130

fixed on the tone arm, a V-shaped oscillatable switch arm arranged in the path of the movement of said finger, one arm of said switch adapted to be engaged and swung by said finger to a fixed circuit closing contact to start the motor, the other arm of said switch as arranged to be engaged and moved by said finger when the tone arm is swung in the opposite direction, to open said circuit.

4. The structure specified in claim 1, and a scratch filter incorporated in said pick-up circuit.

5. The structure specified in claim 1, in which said means for controlling the current to both pick-ups comprises a rheostat with one terminal connected with one pick-up and the other terminal connected to the other pick-up, direct current transmitting means to said pick-ups, a synchronizing control arm operable on said rheostat between its terminals to selectively increase or decrease the current to the pick-ups, circuit wires from said control arm and a secondary resistance coil in said latter circuit comprising a volume control.

6. In an electric record-playing machine having two record turn-tables, a pair of electric pick-ups one each on a tone arm and

operable on a record, a motor for each turn-table, means fixed on each tone arm for closing circuit to the motor of its turntable when pick-up is moved to contacting position said electric circuit closing means being non-contacting with relation to each other when the pick-up is operating over the tone producing area of a record.

7. A music synchronizing attachment for phonographs with two record tables, corresponding tone arms, electric pick-ups, and electric motors rotating said tables; said attachment comprising a manually operated synchronizing control embodying a resistance coil in circuit with both pick-ups and a control lever arranged in circuit with said resistance coil to gradually increase current to one of said pick-ups and simultaneously decrease current to the other pick-up to respectively increase the volume of sound produced by the first pick-up from the record it is in contact with, and to decrease the volume of sound produced by the other pick-up from its record, and a control for volume of sound arranged in circuit between said synchronizing control means and the tone chamber of the phonograph.

In testimony whereof I affix my signature.

FREDERIC H. STROM.
